(57) **CLAIM**

The ornamental design for a supplemental toilet roll dispenser, as shown.

DESCRIPTION

FIG. 1 is a top, front and left side perspective view of a supplemental toilet roll dispenser showing our new design; FIG. 2 is a top, front and left side perspective view thereof, with the broken-line disclosure of a toilet roll holder being for illustrative purposes only and forming no part of the claimed design;

FIG. 3 is a top plan view of one of the bracket portions thereof;

FIG. 4 is a bottom plan view of one of the bracket portions thereof;

FIG. 5 is a front elevational view of one of the bracket portions thereof;

FIG. 6 is a rear elevational view of one of the bracket portions thereof;

FIG. 7 is a left side elevational view of one of the bracket portions thereof;

FIG. 8 is a left side and front perspective view of one of the bracket portions thereof;

FIG. 9 is an inverted front and right side perspective view of one of the bracket portions thereof;

FIG. 10 is a front elevational view of the roller portion thereof;

FIG. 11 is a left side elevational view of the roller portion thereof;

FIG. 12 is a vertical cross-sectional view thereof taken along line 12—12 of FIG. 10; and,

FIG. 13 is a top, front, and left side perspective view of the roller portion thereof.
